DESIGN FOR A DOLL OR BABY CARRIAGE

Carl Hedstrom, Jr., Gardner, Mass., assignor to
Hedstrom-Union Company, Gardner, Mass., a
corporation of Massachusetts

Application June 17, 1936, Serial No. 63,347

Term of patent 3½ years

To all whom it may concern:

Be it known that I, Carl Hedstrom, Jr., a citizen of the United States, residing in Gardner, in the county of Worcester and State of Massachusetts, have invented a new, original, and ornamental Design for Doll or Baby Carriage, of which the following is a specification, reference being had to the accompanying drawing, forming part thereof.

Fig. 1 is a side elevation,
Fig. 2 is a front end elevation,
Fig. 3 is a plan view, and
Fig. 4 is a perspective view of the doll or baby carriage showing my new design.

I claim:

The ornamental design for a doll or baby carriage, as shown.
